Patented Oct. 26, 1971

222,482

TIE RACK

Goodwin Salkoff, Coral Gables, Fla., assignor to
Cosas, Inc., Miami, Fla.

Filed Aug. 3, 1970, Ser. No. 24,274

Term of patent 14 years

Int. Cl. D6—99

U.S. Cl. D33—8

FIG. 2

FIG. 1

FIG. 3

FIG. 4

FIG. 8

FIG. 6

FIG. 5

FIG. 7

FIG. 1 is a side elevational view of a tie rack showing my new design.

FIGS. 2 and 3 are top and bottom plan views.

FIG. 4 is an end view.

FIG. 5 is a side elevational view with the tie receiving arms swung to their retracted position.

FIGS. 6 and 7 are top and bottom plan views.

FIG. 8 is an end view thereof.

I claim:

The ornamental design for a tie rack, substantially as shown.
